United States Patent Office

Des. 224,784
Patented Sept. 19, 1972

224,784

COMBINED SELF-SCAN DISPLAY AND KEYBOARD CONTROLS

Jay Sucre, Exton, Pa., and William A. Hoffman, Collingswood, N.J., assignors to Burroughs Corporation, Detroit, Mich.

Filed Sept. 21, 1970, Ser. No. 25,125

Term of patent 14 years

Int. Cl. D14—02

U.S. Cl. D26—5

Fig. 1

Fig. 2

Fig. 3

Fig. 4

FIG. 1 is a top front and side perspective view of our new design for a combined self-scan display and keyboard controls.

FIG. 2 is an exploded perspective view of the top, front and left sides of the combined self-scan display and keyboard control in a separated fashion.

FIG. 3 is a side view of the combined self-scan display and keyboard controls.

FIG. 4 is a rear view thereof.

We claim:

The ornamental design for a combined self-scan display and keyboard controls, as shown and described.
